WIRE WINDING TOOL

Permil N. Nelson, Galesburg, Ill., assignor to Lynn H. Ewing, doing business as Blackhawk Company, Rock Island, Ill.

Filed Jan. 6, 1965, Ser. No. 423,691
4 Claims. (Cl. 140—117)

My invention relates to a new and useful improvement in a wire winding tool and more particularly to a device for fastening a segment of wire intermediate the ends of a continuous strand of wire by winding the ends of the segment of wire in opposite directions about a continuous strand of wire.

A principal object of my invention is to provide in a tool of this character a means for releasably positioning the tool onto a continuous strand of wire intermediate its ends so that the tool may be readily and easily rotated about the longitudinal axis of the continuous strand of wire as it operates to fasten thereto a second segment of wire.

A further object of my invention is in the provision in a tool of this character of a means for engaging the free end of a segment of wire to be used as a fastener, and winding and coiling the same upon and about a continuous strand of wire intermediate the ends thereof.

A still further important object of my invention is in a tool of this character that is small and compact in size, highly portable, simple in construction, economical to manufacture and efficient in use.

Other objects will appear hereinafter.

The invention consists in the novel combination and arrangement of parts to be hereinafter described and claimed.

The invention will be best understood by reference to the accompanying drawings showing the preferred form of construction, and in which:

FIG. 1 is a perspective view of my wire tool;

FIG. 2 is a perspective view of my tool shown from its opposite side;

FIG. 3 is a fragmentary elevational view showing my tool as applied onto a strand of wire;

FIG. 4 is a top plan view of one form of a fence post with a wire fastener applied by use of my invention;

FIG. 5 is a top plan view of another form of fence post showing the wire fastener as applied by the use of my invention;

FIG. 6 is a fragmentary sectional detail view showing a modified form of my improved tool; and

FIG. 7 is a perspective view of a modified form of my improved tool.

One of the objects of my invention is to provide a tool which may be employed to fasten a wire woven fence to fence posts without the use of the conventional staple type fasteners or expensive wire fasteners now commercially employed. By the use of my invention a simple length of wire may be employed as a fastener for securely attaching a wire fence to a fence post.

My improved wire winding tool, as illustrated in the drawings, showing the preferred embodiment of my invention, comprises a solid circular body 10 having substantially flat parallel end walls 11 and 12. The body 10 is to be constructed of a suitable material which gives the tool the needed tensile strength to accomplish its stated objects.

A passage 13 is provided in the body 10 by forming therein a slot through a radius of the body 10 as shown in FIGS. 1 and 2. The body 10 has a fixed handle 14 extending from the side wall 15 thereof. As shown in FIG. 1, such handle 14 is offset longitudinally of the horizontal center line of the body 10, and lies in the same longitudinal

2

axis described by a movable handle 16 which extends in an opposite direction from the side wall 15.

The movable handle 16 is provided with a threaded end 17 which is adapted to be threadably received in an internally threaded opening 18 formed in the body 10. This opening 18 is in open communication with the passage 13 at a point outwardly of the inner wall 19 of the passage 13 so that upon the threading of the handle 16 into the opening 18 the tapered end 20 of the handle will protrude into and transversely through the passage 13 at a point removed from the inner wall 19 and offset laterally with respect to the center line of the body 10, as seen in FIG. 3.

Projecting tangentially outwardly from the face of the end wall 11 is an engaging means in the form of a circular stud 21. This stud 21 lies in the same longitudinal axis defined by the fixed handle 14 and movable handle 16, as clearly shown in FIG. 3.

In FIGS. 4 and 5, I have shown fragmentarily a V-type fence post 22 and a semi-circular fence post 23, respectively, which are the most common types of fence posts employed in supporting a wire fence.

As can be determined from FIGS. 4 and 5, a continuous strand of wire fencing 24 extends transversely to the longitudinal length of the fence posts 22 and 23. A fastener 25, which is made up from a short segment of wire, is passed around the sides of the post with its free ends extending beyond the continuous strand of wire fencing 24. The free end 25' of the wire fastener 25 is manually bent into a position where it extends substantially perpendicular to the longitudinal axis of the strand of wire fencing 24 as shown in FIG. 3. The tool then is placed upon the strand of wire fencing 24. This is accomplished by rotating the movable handle 16 so as to thread the same out of communication with the passage 13 formed in the body 10. The body 10 is then placed on the wire 24 and the movable handle 16 is again threaded into the body 10 until the tapered end 20 thereof releasably secures the wire 24 between the inner wall 19 of the passage 13 and such tapered end 20 of the handle 16 as shown in FIG. 3.

In this position of the tool on the wire 24, the circular stud 21 will engage the free end 25' of the fastener wire 25 and upon rotation of the body 10 about the longitudinal axis of the wire fencing 24, such free end will be caused to be wound or coiled into the conditions shown in FIGS. 4 and 5. The operation is repeated on the opposite side of the post so as to readily secure the wire fencing 24 to the post.

In FIG. 6 I show a modified form of my improved wire winding tool wherein in place of the movable handle 16, I have provided a spring urged ball detent. As shown in FIG. 6, an aperture 26 is formed in the body 10 in which is positioned a spring 27 and ball detent 28. A handle member 29 is fixedly journaled into the opening 26 so as to retain the spring urged ball detent in place. With the modified structure, the operator need only to force the wire 24 into the passage 13 over and beyond the ball detent 28 to releasably attach the body to the wire.

In FIG. 7 I show a modified form of my improved wire winding tool which comprises an elongated rectangularly shaped body member 30. Positioned on one side face 31 of the body member 30 is an elongated flat spring latch member 32 which has one end 33 connected by means of a rivet 34 to the body member 30 so that the spring latch 32 lies in substantial facial abutment with the one flat side 31 of the body 30. The free end of the spring latch 32 is deformed out of the normal longitudinal plane thereof as at 35 to provide a wire receiving groove. Slidably embracing the body 30, as well as the spring latch 32 is a movable clip 36. When

the clip 36 is moved in one direction over the spring latch 32 and body 30, it will engage the deformed portion 35 of the spring latch 32 and cause the same to be yieldably held against the side face 31 of the body 30. When the slide 36 is moved in the direction of the rivet 34 the free end of the spring latch 32 may be caused to be displaced slightly from the face 31 of the member 30 so that a strand of wire may be received in the wire receiving groove formed by the deformed portion 35. When the slide 36 is again moved away from the rivet 34 it will yieldably connect the wire strand to the body 30.

Carried by the body 30 is a laterally extending finger plate 37. This finger plate functions in the same manner as the circular stud 21 hereinbefore defined so that when the body 30 is connected to a wire strand as hereinbefore explained, the finger 37 will engage the free end of a fastener wire and cause the same to be coiled about the wire strand when the body 30 is rotated about the axial plane of the wire fencing or the like.

From the foregoing, it is readily apparent that I have devised a simple tool which is simple to operate, yet highly effective in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A tool for winding the ends of a wire fastener about a strand of continuous wire for connecting the same together comprising

- (a) a body member,
- (b) a passage extending through the body following a radius thereof for receiving a portion of a continuous wire intermediate its ends,
- (c) a means for releasably holding said portion of said continuous wire in said passage while permitting rotation of said body member about the longitudinal axis of said wire,
- (d) a means carried by said body for engaging the free end of the wire fastener for winding said free end about the continuous strand of wire upon rotation of said body about the longitudinal axis of said strand of wire for fastening the wires together,
- (e) said means for releasably holding a portion of said continuous wire in said passage comprising an elongated element movable longitudinally through a segment of said body and into said passage at a point removed from the inner end wall of said passage a distance greater than the thickness of the continuous strand of wire so as to loosely retain said wire within said passage and said body rotatable thereon.

2. A tool as defined by claim 1 and further characterized by including a handle provided by said body to facilitate rotating the same about the longitudinal axis about said strand of wire so as to cause the free end of

said fastener to be coiled or wound about said continuous strand of wire for connecting the same together.

3. A tool for winding the ends of a wire fastener about a strand of continuous wire for connecting the same together comprising

- (a) a compact circular body having substantially flat opposite side walls,
- (b) a passage extending through the body following a radius thereof for receiving a portion of a continuous wire intermediate its ends,
- (c) a means for releasably holding said portion of said continuous wire in said passage while permitting rotation of said body member about the longitudinal axis of said wire,
- (d) a wire engaging stud extending tangentially from one of said flat side walls of said body for contacting the free end of said wire fastener upon the rotation of said body about the longitudinal axis of said continuous strand of wire in the direction defined by the tangentially extending stud for winding said free end of said wire fastener about the continuous strand of wire for fastening the wires together,
- (e) said means for releasably holding a portion of said continuous wire in said passage comprises an elongated element movable longitudinally through a segment of said body and into said passage at a point from the inner end wall of said passage a distance greater than the thickness of the strand of wire so as to loosely retain said wire within said passage and said body rotatable theron.

4. A tool for winding the ends of a wire fastener about a strand of continuous wire for connecting the same together comprising

- (a) a body member,
- (b) means for removably connecting said body member to a portion of a continuous wire intermediate its ends while permitting rotation of said body member about the longitudinal axis of said continuous wire, and
- (c) a means carried by said body for engaging the free end of the wire fastener for winding said free end about the continuous strand of wire upon rotation of said body about the longitudinal axis of said strand of wire for fastening the wires together,
- (d) said means for removably connecting said body member to a portion of a continuous wire intermediate its ends comprises a spring latch and a movable clip member for maintaining said spring latch in a wire holding position.
